UNITED STATES PATENT OFFICE

OLA IRENE HETZER, OF SEATTLE, WASHINGTON

DESIGN FOR A STATUETTE FOR BARBER SHOPS OR BEAUTY PARLORS

Application filed February 12, 1930. Serial No. 34,489. Term of patent 7 years.

To all whom it may concern:

Be it known that I, OLA IRENE HETZER, a citizen of the United States, residing at Seattle, in the county of King and State of Washington, have invented a new, original, and ornamental Design for a Statuette for Barber Shops or Beauty Parlors, of which the following is a specification, reference being had to the accompanying drawings, forming a part thereof.

In the accompanying drawings Figures 1 to 4 inclusive are views in elevation showing the four sides of the statuette taken from positions at intervals of substantially ninety degrees.

I claim:

The ornamental design for a statuette for barber shops or beauty parlors, as shown.

OLA IRENE HETZER.
